ATTORNEY

UNITED STATES PATENT OFFICE.

ROBERT E. NEILSON, OF TULSA, OKLAHOMA.

SAND PUMP.

Application filed June 27, 1927. Serial No. 201,829.

My invention relates to sand pumps and more particularly to a device of that character for removing sand and débris from the pocket of an oil well, for sampling or cleaning of the pocket, and which may be employed for introduction of chemicals or hot water to the well pocket to dissolve paraffine formation in the sands and thereby stimulate flow of oil from the sands to the well.

10 The invention has for its principal object to provide a pump of this character which will positively retain its charge of sand fluid or chemical during the letting-in travel of the pump; whereby clogging of the intake 15 is avoided; whereby point of intake of the sand may be regulated; and whereby fluid content of the well pocket may be agitated to insure intake of the sand and like débris which it is desired to remove from the well.

20 In accomplishing these and other objects of the invention I have provided improved details of structure, the preferred forms of which are illustrated in the accompanying drawings, wherein:

25 Fig. 1 is a vertical section of the lower portion of an oil well, illustrating application of my improved sand pump thereto.

Fig. 2 is an enlarged longitudinal section of the pump, showing the intake valve open.

30 Fig. 3 is a similar view, showing the valve closed.

Fig. 4 is a detail view of one of the parts.

Referring more in detail to the drawings:

35 1 designates an oil well, extending through cap rock 2 above the oil sand 3 and terminating in a pocket 4 formed by shooting the well in accordance with common practice. 5 designates sand and like débris accumulated in the bottom of the pocket as a result 40 of shooting of the well, from natural dislodgment from the walls of the pocket, or from scouring of the walls with a reaming tool.

The part of the well above the cap rock is 45 lined with a casing 6 supported by a shoe 7 from the cap rock, and extending through the casing into the upper portion of the pocket is the ordinary tubing 8.

My sand pump, intended for use in a well 50 like that above described, comprises a barrel 9 closed at its upper end by a threaded plug 10, preferably provided with a toothed shank 11 for engagement by fishing tools in case of loss of the pump in the well, and having

a central bore 12 through which a piston rod 13 is slidably projected. At its lower end the barrel is provided with interior screw threads 14 for receiving a closing plug or gauge leg 15 whereby intake to the cylinder from its lower end is prevented and whereby lowering of the pump into the well is regulated to locate intake ports at any desired point above the bottom of the pocket according to the length of the gauge leg.

The barrel is cut away adjacent its lower end to provide the lateral ports 16, and fixed within the barrel, directly above the ports and by rivets or the like 17, is an interior sleeve 18 on which is formed a valve seat 19. Slidably mounted within the barrel above 70 the sleeve 18 is a spider 20, comprising a central circular head 21 having a central aperture 22 and radial wings 23, having their ends curved to fit snugly in guided relation with the inner wall of the barrel. The upper face of the central head is provided with a ball race groove 24 adapted to register with a race groove 26 in the lower face of a nut 27 threaded to the shank 28 of a valve stem 29 which extends through the port 30 in the 80 sleeve 18, into the lower portion of the pump cylinder and carries a valve 31 adapted for engagement in the seat 19 to close the port 30. Bearing balls are located in the race 85 grooves in the spider and nut so that the stem may swivel on its mounting and the valve rotate in its seat to effect removal of sand or foreign matter which might interfere with proper seating of the valve. The valve 31 is removable from the stem 19 but 90 ordinarily held rigidly thereto by a nut 32 threaded on the shank 33 of the stem. The stem is removable from the spider but normally held thereto by the nut 27 and lock nuts 34.

The wings 23 of the spider 20 are provided with apertures 35 seating the shanks 36 of extender and guide rods 37 which latter are of a length to extend to near the upper end of the cylinder, where they are connected with a disk 38, slidably within the barrel but snugly fitting the same to prevent accumulation of sand within the barrel above the disk. The rods 37 are preferably riveted to the spider 20 and to the disk 38, forming 100 105 a rigid connection therebetween.

Located within the barrel, above the disk 38 and bearing against the disk and against

the inner face of the plug 10, is an expansion spring 40 which yieldingly urges the disk 38, the rods 37 and the spider 20 downwardly in the pump cylinder to seat the 5 spider on the upper rim of the valve sleeve 18 and thereby unseat the valve 31 and open the interior of the barrel to the lateral ports 16.

Slidably mounted on the rods 37 is a 10 piston 41 having apertures 42 through which the rods 37 are passed to permit the piston to slide on the rods and having a central aperture 43 for the shank 44 of the rod 13 which extends slidably through the channel 15 12 in the head plug 10 and through a channel 45 in the disk 38. The piston is preferably provided with an annular packing 46 and a retainer plate 47 held to the piston body by nuts 48 and 49 on the rod 13 and 20 its shank 44 at opposite sides of the piston.

The upper end of the rod 13 is provided exteriorly of the barrel with a swivel coupling 50 for connecting the rod with a rope or cable 51 whereby the pump may be let 25 into and removed from the well and whereby the pump piston may be operated when the pump is set.

52 designates clean-out holes in the upper end of the barrel, through which sand escaping 30 past the piston and the disk 38, may be removed.

Assuming the parts to be constructed and assembled as described and the pump intended for use for bailing sand from a well 35 pocket, the operation is as follows:

The pump is suspended from the well cable through the coupling on the piston rod; the weight of the barrel and its contained parts causing the piston to engage the 40 disk 38 on the upper ends of the guide rods and hold the disk so that the barrel is lowered thereover, compressing the spring 40 and lifting the spider 20 so that the valve 31 is lifted to its seat, closing intake to the 45 barrel. With the parts in this relation and the valve closed, the pump is let into the well and through the well fluid into the well pocket. When the pump rests on the bottom of the well, weight of the piston rod and 50 the cable causes the piston to move down along the guide rods, relieving the spring 40 so that it pushes against the disk 38 and, aided by the weight of the piston rod and cable, forces the spider 20 downwardly, 55 thereby opening the valve so that fluid in the pocket may pass through the radial ports in the barrel and through the port 30 in the valve sleeve 18 into the interior of the barrel.

When the pump has been set, the piston 60 may be reciprocated with short strokes to draw fluid into the pump and force the fluid from the pump to agitate the fluid and stir up the sand. The sand-laden fluid is then drawn into the barrel by lift of the piston, 65 the piston engaging the disk 38 as it reaches

the top of the barrel to lift the disk, the guide rods and the spider and thereby lift the valve 31 to seat it and trap the sand-laden fluid within the barrel.

The pump is then pulled from the well 70 and, upon reaching the surface, is let down to relieve the valve, which automatically opens under tension of the spring 40 to discharge the load.

It is apparent that with a pump constructed in accordance with my invention there is no danger of the intake being clogged by seating of the barrel in the sand bed, that the elevation at which the fluid is admitted to the pump may be regulated according to 80 the length of the gauge leg 15 and that because of the suspension of the pump from the valve through the piston rod and guide elements, the valve is positively closed during lift of the pump from the well, thereby 85 preventing loss of the fluid during the upward travel of the pump through the well.

If the pump is to be used for delivering chemical or hot water to the well for removal of paraffine, the pump is charged at the surface and let into the well pocket until the weight of the pump is supported from the bottom of the well, when the valve will automatically open to discharge the load laterally against the wall of the pocket, thereby 95 adding mechanical force of the discharging fluid to the chemical or heating effect of the cleaning liquid to remove the paraffine from the pores of the sand.

What I claim and desire to secure by Letters Patent is:

1. A pump of the character described including a barrel having an intake port at its lower end, a valve seat in the barrel above the intake port, a piston in the barrel, an extender having connected heads at opposite sides of the piston, a valve suspended from the lower extender head, a rod on said piston extended through the upper head to the exterior of the barrel, and means for suspending the pump from the piston and its rod.

2. A pump of the character described including a barrel having an intake port at its lower end, a valve seat in the barrel above said port, an extender longitudinally movable in the barrel above the valve seat comprising heads and spacing guide rods, a valve suspended from the lower extender head, a piston slidably on the guide rods and engageable with the upper extender head to lift the valve to its seat, a rod on the piston, and means for suspending the pump from said rod.

3. A pump of the character described including a barrel having an intake port at 125 its lower end, a valve seat in the barrel above said port, an extender longitudinally movable in the barrel above the valve seat comprising heads and spacing guide rods, a valve suspended from the lower extender head, a 130

piston slidable on the guide rods and engageable with the upper extender head to lift the valve to its seat, means yieldingly urging the extender to space the valve from its seat, a rod on the piston, and means for suspending the pump from said rod.

4. A pump of the character described, including a barrel having lateral openings adjacent its lower end, a valve seat in the barrel above the openings, an extender comprising upper and lower head members and connecting rods, a valve for said seat having a stem fixed to the lower extender head, a piston in the barrel between the extender heads and engageable therewith to seat or unseat said valve, and a rod on said piston extended through the upper end of the barrel.

5. A pump of the character described, including a barrel having lateral openings adjacent its lower end, a valve seat in the barrel above the openings, an extender comprising upper and lower head members and connecting rods, a valve for said seat having a stem fixed to the lower extender head, a piston in the barrel between the extender heads and engageable therewith to seat or unseat said valve, a plug closing the upper end of the barrel, and a rod on said piston slidably extended through said plug to the exterior of the barrel.

6. A pump of the character described, including a barrel having lateral openings adjacent its lower end, a valve seat in the barrel above the openings, an extender comprising upper and lower head members and connecting rods, a valve for said seat having a stem fixed to the lower extender head, a piston in the barrel between the extender heads and engageable therewith to seat or unseat said valve, a plug closing the upper end of the barrel, a rod on said piston slidably extended through said plug to the exterior of the barrel, and an expansion spring

in the barrel between said upper head and said plug.

7. A pump of the character described, including a barrel having lateral openings adjacent its lower end, a valve seat in the barrel above the openings, an extender comprising upper and lower head members and connecting rods, a valve for said seat having a stem fixed to the lower extender head, a piston in the barrel between the extender heads and engageable therewith to seat or unseat said valve, a rod on said piston extended through the upper end of the barrel, and a pump supporting leg closing the lower end of the barrel.

8. A pump of the character described, including a barrel having lateral openings adjacent its lower end, a valve seat in the barrel above the openings, an extender comprising upper and lower head members and connecting rods, a valve for said seat having a stem fixed to the lower extender head, a piston in the barrel between the extender heads and engageable therewith to seat or unseat said valve, a plug closing the upper end of the barrel, a rod on said piston slidably extended through said plug to the exterior of the barrel, and an expansion spring in the barrel between said upper head and said plug, the barrel having clean-out openings adjacent its upper end.

9. A pump of the character described, including a barrel having lateral openings adjacent its lower end, a sleeve in the barrel above said openings forming a valve port and seat, an extender in the barrel comprising upper and lower heads and connecting rods, a valve having a stem swivelly suspended from the lower extender head, and a piston in said barrel between the extender heads, and having a rod extending upwardly to the exterior of the barrel.

In testimony whereof I affix my signature.
ROBERT E. NEILSON.
